SOUND COLLECTING SYSTEM

Edward W. Kellogg, Moorestown, N. J., assignor
to Radio Corporation of America, a corporation
of Delaware

Application December 31, 1937, Serial No. 182,720

6 Claims. (Cl. 181—26)

This invention relates to sound collecting systems, and more particularly to a microphone system of the directive type.

Many attempts have been made to provide a microphone which is sensitive to sound coming from a particular source and in a particular direction and insensitive to sounds coming from other directions. Among the proposals heretofore made has been the almost obvious one of placing the microphone at the focal point of a large parabolic reflector with the reflector facing the direction from which it is desired to pick up the sound. The results have not usually been satisfactory, however, with such a system probably because, if the parabola is made large enough to give appreciable concentration of low frequency sounds, it becomes so sharply directive for high frequency sounds that it can not be aimed sufficiently accurately. For example, the directive characteristics of such a system show that, at the high frequencies, certain components will be cancelled out if the source is not exactly on the axis. One attempt to lessen this effect at the high frequencies consists in using a parabola of smaller base diameter and of considerable depth or length. However, it has been found that with such a reflector, objectionable resonances occur. When deep reflectors have been used, resort has been had to attaching Helmholtz resonators near the microphone so that the excess sound will be absorbed at certain frequencies. Another fault which is almost always encountered when sound concentrators of the lens or the parabolic reflector type are used is that the high frequency components are strongly reinforced while those of lower frequency are less affected, with the result that the sound picked up by the microphone is badly unbalanced. If the reflector is made large enough to be effective at low frequencies, the concentration of the high frequency components is still further increased.

The primary object of my present invention is to provide an improved sound collecting system of the type under consideration which will be free from the foregoing and other similar defects of prior art systems.

More specifically, it is an object of my present invention to provide an improved sound collecting system as aforesaid which will be sufficiently directive for both high and low frequency sounds without having such extreme directivity at certain frequencies as to make it difficult to secure good results.

Another object of my present invention is to provide an improved sound collecting system

which need not be aimed with extreme accuracy toward the sound source in order to receive sound therefrom in the desired direction.

Still another object of my present invention is to provide an improved sound collecting system of the type described which will have a characteristic free from objectionable resonant peaks. 5

It is also an object of my present invention to provide an improved sound collecting system as aforesaid which is extremely simple in construction and highly efficient in use. 10

In accordance with one form of my present invention, I provide a parabolic reflector having a large diameter and place a suitable microphone substantially at the focus thereof. The large 15 diameter is necessary to obtain reinforcement and directivity at low frequencies, but since the use of only a small portion of the reflector is desirable for the high frequency sounds, I line the interior surface of the reflector in a region near 20 its outer edge with a suitable sound absorbing material which will absorb the high frequency sounds much more than the low frequency sounds. For this purpose may be used layers of 25 felt of moderate thickness, the thicker the layers the lower being the frequency at which they become effective absorbers. Preferably, the felt or other similar porous lining is made of gradually varying thickness with the thickest part 30 thereof at the edge, or mouth, of the reflector and the lining extending inwardly of the reflector a distance such as to leave a relatively small area 35 at the center of the reflector free from covering. As a result, the outer, or lined, portion of the reflector will not reflect much high frequency sound, and the directivity at the high frequencies can be reduced to the desired point. On the other hand, the low frequency sounds, which will be reflected to the microphone in spite of the felt lining, will utilize larger areas of the reflector, 40 and thereby sufficient overall directivity and reinforcement will be obtained. In some cases, it may be found desirable to alter the curvature of the reflector, departing slightly from a true parabola, to compensate for the shift of phase of the 45 waves that are reflected from the felt covered area.

According to another form of my present invention, I employ a suitable sound lens instead of a reflector and place the microphone at substantially the focus of the lens. The outer portions 50 of the lens (that is, in a region adjacent the periphery thereof) can be covered with an annulus of felt or other suitable sound absorbing material of gradually varying thickness to provide selective 55

absorption of the high frequency sounds, or the walls of the lens itself may be made of gradually varying thickness, being thickest at the outer edge, or periphery. This will tend to reflect more 5 of the high frequency sounds and transmit less thereof, whereas the low frequency sounds will be less affected by the thicker wall portion of the lens.

The novel features that I consider characteristic 10 of my invention are set forth with particularity in the appended claims. The invention itself, however, both as to its organization and method of operation, together with additional objects and advantages thereof, will be best understood 15 from the following description of several embodiments thereof, when read in connection with the accompanying drawing in which

Figure 1 is a view showing a sound collecting system which includes a reflector and microphone 20 according to conventional practice,

Figure 2 is a similar view of a sound collecting system according to my present invention,

Figure 3 is a view similar to Fig. 1 but showing diagrammatically a sound collecting lens instead 25 of a reflector,

Figure 4 is a view similar to Fig. 3 but arranged according to my present invention, and

Figure 5 is a view similar to Fig. 4 but showing a somewhat different embodiment of the modification 30 of my invention shown in Fig. 4.

Referring more particularly to the drawing, wherein similar reference numerals designate corresponding parts throughout, there is shown, in Fig. 1, a parabolic reflector 1 at substantially the 35 focal point 3 of which is located a suitable microphone or other sound wave responsive device 5. The reflector 1 is made of large diameter at its base or mouth 7, in order, as pointed out previously, to obtain directivity for low frequency 40 sounds. Such a system is representative of prior art systems and is open to the objections previously mentioned, particularly that the reflector 1 is so sharply directive for high frequency sounds that it cannot be aimed accurately enough toward the sound source which is being picked up.

To remedy this defect, I have provided the system shown in Fig. 2. The parabolic reflector 1 of this system may be similar to that shown in Fig. 1, but it has a diameter at the mouth 7 of 50 the order of at least one wave length of the lowest frequency to be concentrated, and it is provided on its reflecting surface with a covering or lining 9 of felt or other suitable porous material. The lining 9 is of gradually varying 55 thickness and extends substantially from the mouth 7 of the reflector 1 inwardly a distance short of the central region 11 of the reflector 1, leaving the central region 11 entirely uncovered. The lining 9 is thickest over the zones 60 adjacent the mouth 7 and thinnest adjacent the uncovered central region 11 of the reflector. It is the property of layers of felt of moderate thickness that they absorb high frequency sounds much more readily than the low frequency 65 sounds, and the thicker the layer the lower is the frequency at which it becomes an effective absorber. By covering the reflecting surface of the reflector 1 with a lining 9 of gradually varying thickness, with the thickest portion 70 thereof at the edge, or mouth, of the reflector, and with the central area 11 left uncovered, the covered portion of the reflector will not reflect much high frequency sound. Accordingly, the directivity of the system at the higher frequencies 75 is reduced to the desired point, it being apparent

that there is less reflection of the high frequency waves toward the microphone 5 adjacent the base or mouth 7 than adjacent the uncovered region 11, and by far most of the reflection of the high frequency waves toward the microphone 5 taking place at the uncovered region 11. Since, however, the low frequency waves are reflected in spite of the felt lining 9, it will be apparent that much larger areas of the reflector 1 will be utilized in reflecting the low frequency 10 sounds toward the microphone, and thus sufficient over-all directivity will be obtained without having any undesirable concentration and excessive directivity in the high frequency range. The effect, it will be seen, is equivalent to providing a large diameter mirror for low frequency sounds and progressively smaller mirrors for higher frequencies.

In Fig. 3, there is shown a system functionally similar to that of Fig. 1, but employing a sound lens 21 instead of the reflector 1, the microphone 5 being located substantially at the focal point 23 of the sound lens. The sound lens 21 is constituted by a pair of very thin membranous elements 25 and 27, such as sheet rubber or oiled silk, sealed at their peripheries to provide a hollow structure or chamber therebetween filled with a heavy gas. The system shown in Fig. 3 is objectionable similarly to that shown in Fig. 1. In accordance with my invention, I provide an annular covering 29 of felt or the like, on either one or both of the membranes 25, 27, as may be desired, only the member 25 in Fig. 4 being shown as provided with the felt covering 29. As in the system of Fig. 2, the felt covering 29 extends from substantially the periphery of the lens 21 radially inwardly a distance short of the radius of the lens, so as to provide a central region 31 which is uncovered. The annular covering 29, like the 35 lining 9, is of gradually varying thickness, being thickest adjacent the periphery of the lens and thinnest adjacent the central, uncovered region 31, and providing selective absorption of the high frequency sounds, the absorption being greatest 40 adjacent the periphery of the lens.

In Fig. 5, I have shown a modified form of the last-described embodiment of my invention. In this modification, the felt covering 29 is dispensed with and the membranes 25 and 27 are 50 made of gradually varying thickness from the periphery to the central regions 31 which is thinnest and of substantially uniform thickness throughout. Either one or both of the membranes 25 and 27 may be made in this manner, 55 Fig. 5 showing them both so formed. It is in general preferable in a lens such as shown in Fig. 5 to apply the thickening for the most part to the membrane on the side toward the source of sound, thus preventing the undesired sound 60 from entering the lens, where it would be subjected to successive internal reflections, and perhaps in some measure reach the microphone. With the embodiments of my invention shown in Fig. 4 and Fig. 5, the high frequency waves 65 are reflected more and more as the periphery of the lens is approached, so that less of the high frequency sounds will be transmitted through the lens. On the other hand, the low frequency waves are affected much less by the 70 thickened portions of the walls 25 and 27 or by the covering 29, as the case may be, and practically all of the low frequency waves are transmitted by the lens 21. Again, therefore, an improved over-all directivity will result.

Although I have shown and described several embodiments of my invention, it will be apparent to those skilled in the art that many other modifications are possible. I therefore desire that my invention shall not be limited except insofar as is made necessary by the prior art and by the spirit of the appended claims.

I claim as my invention:

1. A sound collecting system comprising means having a predetermined focal point for receiving and directing sound waves from said direction to a predetermined focal point, said means having a central region and a periphery, and sound wave responsive means located at substantially said focal point and arranged to be actuated by said sound waves, said first-named means including a variable frequency discriminating means for directing waves of certain frequencies to said focal point more readily than waves of certain other frequencies, and said frequency discriminating means extending from substantially said periphery to said central region.

2. A sound collecting system comprising means for receiving and directing sound waves from a predetermined direction to a predetermined focal point, said means including a central region and a periphery, sound wave responsive means located at substantially said focal point and arranged to be actuated by said sound waves, and means carried by said first-named means adapted to direct sound waves of different frequencies to said focal point as a function of its thickness, said last-named means extending from said periphery to a region short of said central region and having a gradually varying thickness with its thickest portion adjacent said periphery and its thinnest portion closest to said central region.

3. A sound collecting system comprising a substantially parabolic reflector, a microphone lo-

cated at substantially the focal point thereof, and a lining of felt on the reflecting surface of said reflector, said lining extending from substantially the mouth of said reflector to a region short of the central region thereof, and said lining being of gradually varying thickness with its thickest portion adjacent said mouth and its thinnest portion adjacent said central region.

4. A sound collecting system comprising a sound lens, a microphone located at substantially the focal point thereof, a covering of felt on said sound lens, said covering extending from substantially the periphery thereof radially inwardly a distance short of the radius of said lens whereby to provide an uncovered central region on said lens, and said covering being of gradually varying thickness with its thickest portion adjacent said periphery and its thinnest portion adjacent said central region.

5. A sound collecting system comprising, in combination, a sound lens and a microphone located at substantially the focal point thereof, said sound lens comprising a sealed, hollow membranous element having a gas therein, and said membranous element being of varying thickness.

6. A sound collecting system comprising, in combination, a sound lens and a microphone located at substantially the focal point thereof, said sound lens comprising a sealed, hollow membranous element having a gas therein, and said element being of gradually varying thickness with its thickest portion adjacent the periphery, the thickness of said element being gradually reduced radially inwardly a distance short of the radius of said lens and the central region of said member being of substantially uniform thickness and constituting the thinnest portion of said element.
